UNITED STATES PATENT OFFICE.

EGBERT H. GOLD, OF EVANSTON, AND EDWARD A. RUSSELL, OF CHICAGO, ILLINOIS;
SAID RUSSELL ASSIGNOR OF HIS ONE-HALF TO VAPOR CAR HEATING COMPANY,
INC., OF CHICAGO, ILLINOIS, A CORPORATION OF NEW YORK.

FLEXIBLE JOINT.

Original application filed March 17, 1922, Serial No. 544,448. Divided and this application filed March 18, 1926. Serial No. 95,805.

Our invention relates to a conduit or tubular structure consisting of metal elements flexibly articulated so as to form a fluid tight connection between the train pipes of the adjacent cars of a railroad train, to take the place of the rubber hoses ordinarily used for this purpose. The complete connection consists in each case, of two flexible structures, one for each of the train pipes, to be connected, these structures being coupled together by any suitable means, for example, the couplers such as are used with the rubber hoses heretofore generally employed for making this connection.

The conduit consists, in general, of a vertically disposed conduit member, which is suspended from the end of the car train pipe, and a horizontally disposed conduit member supported at one end from the lower end of the vertically disposed conduit member, and carrying at its free end the coupler for engaging the corresponding coupler on the conduit of the adjacent car. Suitable flexible connections of the improved type hereinabove set forth, are employed to support the vertically disposed conduit member from the car, and the horizontally disposed conduit member from the vertical conduit member, so that the requisite flexibility is permitted, first, to permit the engagement or disengagement of the couplers, and, second, to allow the articulated members a range of movements necessary in order that the connection may accommodate itself to the movements of the car with respect to the adjacent car when the train rounds curves or passes over inequalities in the track.

When the car is at the end of the train the pipe connecting structure at the rear extremity of the car, will, obviously, have no mating element to be coupled with, and in such case it is necessary to have a supporting device for the coupler and the horizontally extending conduit member, else these parts will hang down and be damaged by contact with the ties or other parts of the track or roadbed. This improved conduit structure embodies an improved and simple device for permanently supporting the outer end of the pipe connecting structure and holding the same at a safe distance above the roadbed, this improved supporting device being disclosed and claimed in our

co-pending application, Serial No. 544,448, filed March 17, 1922, now Patent No. 1,589,558, dated June 22, 1926, of which this present application is a division.

The principal object of this invention is to provide an improved lubricating means for the articulating connections of a metallic conduit of the general type briefly disclosed hereinabove.

Other objects and advantages of this invention will be more apparent from the following detailed description of certain approved forms of the apparatus.

In the accompanying drawings:

Fig. 1 is a view in elevation, of a flexible connection constructed in accordance with our invention, for connecting the steam train pipes of adjacent railway cars.

Fig. 2 is a central vertical longitudinal section through the upper universal joint, and adjacent portions of the flexible conduit.

Fig. 3 is a horizontal section taken substantially on the line 3—3 of Fig. 2.

Fig. 4 is a vertical section through the adapter for attachment of the flexible conduit structure to the car train pipe.

Fig. 5 is a horizontal section taken substantially on the line 5—5 of Fig. 1.

Referring to the drawings, Fig. 1 shows the complete connection as consisting of two identical structures, one attached to one of the train pipes, and the other attached to the train pipe of the adjacent car.

It will be understood, however, that assuming the use of a standard type of coupler, the connecting device or flexible conduit of our invention might be coupled up with any other sort of connecting device, such, for example, as the rubber hose type of connection heretofore commonly used upon the steam or air train pipes of railway cars.

In the flexible metallic conduit structure, as shown in the drawings, 1 is a union or adapter for supporting the flexible conduit structure from the end 2 of the car train pipe, the adapter being angular as shown, so that the flexible conduit structure will hang substantially in a vertical position. In the drawings, the internal diameter of the flexible conduit structure is shown as larger than the internal diameter of the train pipe end valve, and consequently the upper end 3 of the adapter which screws

into the end 2 of the train pipe end valve, is smaller in diameter than the lower end 4 of the adapter into which is screwed the neck portion 5 of the upper socket member. By changing the adapters, the flexible structures, as hereinafter disclosed, may be attached to train pipes of different diameters without altering the flexible conduit structures or the end train pipe valve.

10 The vertically disposed conduit member 6 is suspended from the adapter 1 by means of the flexible joint and articulating connections indicated generally at 7, and the horizontally disposed conduit member 8 is connected by a similar flexible joint 9 with an elbow fitting 10 secured to the lower end of the vertically disposed conduit member 6. The free end of the horizontal conduit member 8 carries the coupler 11 adapted to be joined to a similar mating coupler 12 carried by the flexible conduit structure on the adjacent car. These couplers 11 and 12 are here shown as of the common form of gravity hose couplers adapted to be engaged with or disengaged from a mating coupler by a rocking movement.

The upper flexible joint 7 is adapted to permit universal angular movement of the intermediate vertically disposed conduit member 6, within certain limits, and also permit a swiveling or rotary movement of the conduit member 6 about its central longitudinal axis. This flexible joint comprises a socket member 13, having an upper neck portion 5 adapted to be screwed into the lower end 4 of the adapted 1, as hereinabove described. Into the ring 14 which surrounds the lower end of socket member 13, is fitted a pair of diametrically disposed bushings 15 of brass or bronze. These bushings have closed, preferably conical ends 16 and have a threaded engagement with the ring 14 so that when worn they may be readily removed and replaced. The yoke 17 comprises a central annular neck portion 18, from which arise the oppositely disposed arms 19, into the upper ends of which are screwed the preferably hard steel pivot studs 20, having smooth end portions 21 fitting closely into the bushings 15. Preferably each stud is formed with a central lubricant duct 22 and with radial branch ducts 23 extending from the central duct to the bearing surfaces between the stud and the bushing. In assembling these parts, the bushing 15 is partly filled with a lubricant, which is forced through the ducts 22 and 23 when the stud is screwed down into the bushing. The stud may be held in place, if desired, by any suitable form of nut lock 24.

A pair of bosses 25 extend horizontally at diametrically opposite points from the lower portion of socket member 13, and bushings, similar to the bushings 15, are

preferably mounted in these bosses 25. A pair of pivot studs 26 preferably constructed like the studs 21, are mounted in the ring 14 and are adapted to engage in the bushings in the bosses 25. The pivotal axis of the studs 26 is at right angles to the pivotal axis of the studs 21, that is, the four pivotal connections carried by the ring 14 are positioned at spaced intervals of 90° about the circumference of this ring. 75

The hollow ball member 27, which is adapted to extend loosely into the cylindrical socket 28 in socket member 13, has a downwardly extending neck portion 29 threaded at 30 to engage in the upper end 80 of the intermediate vertically disposed conduit member 6. The neck portion 29 extends down through the central opening in the annular neck portion 18 of yoke 17, and an annular flange or collar 31 on the ball 85 member engages the neck 18 whereby the ball member is supported by the yoke with the ball 27 positioned centrally within the socket 28, but out of contact with the walls thereof. The articulating means just described, serves to support the flexible conduit construction from the adapter 1 and at the same time permits universal angular movement therof by reason of the pivotal connections between the yoke 17 and ring 14 and between the ring 14 and the socket member 13. Also, since the ball member 27 is freely swiveled within the neck portion 18 of the yoke 17, the vertically disposed conduit member 6 can be rotated freely 100 about its central longitudinal axis, in whatever angular position it may assume.

An annular gasket 32, preferably of rubber composition, is slidably mounted within the cylindrical socket 28, and has a lower curved surface 33 adapted to engage the spherical end portion of ball 27. This gasket is forced into place by coiled spring 34, bearing at its upper end against the inner surface of socket member 13, and at 110 its lower end against a metal follower 35, which projects into the gasket 32. The gasket 32 will also be urged into place, to seal the joint between the ball and socket members, by the steam pressure normally existing within the flexible pipe connection. The socket member 13 is formed internally, near its lower edge, with a groove 36 in which is positioned a packing ring 37 which bears against the ball member 27 and is adapted to prevent dust, dirt, cinders, and the like from entering between the ball and socket. 115

The positioning of this flexible joint vertically, so that it operates about a vertical 125 axis, will cause the parts (particularly the gasket 32 and packing ring 37) to wear equally throughout their circumferences, thus increasing the effective life of the joint and insuring a steam-tight-connection at all times, 130

Preferably the intermediate tubular conduit member 6 is inclosed in a heat insulating covering 38, fitting between heads 39 and held in place by clamping straps 40, all 5 as shown in Figs. 1 and 5.

The lower horizontally extending conduit member 8, which carries the coupler 11, is connected with the elbow fitting 10 by means of a flexible joint 9, which in most 10 respects is the same as the flexible joint 7 hereinabove described in detail. However, this flexible joint 9 permits angular movement of the socket member about one axis only, together with a rotary or swiveling 15 movement as in the upper flexible joint. A yoke 41, having a collar 42 swiveled on the end of elbow fitting 10 behind a shoulder 43, is pivoted by means of a pair of horizontally arranged pivot studs 44 to the 20 socket member 45 of flexible joint 9. Thus this joint permits an angular swinging movement of the horizontal conduit member 8 and the coupling 11 about one axis only (normally in a vertical plane), although 25 these members may swivel about substantially the longitudinal axis of this portion of the pipe connection.

The lower or outwardly extending portion 30 of the flexible structure, that is to say, the horizontal conduit member 8, the coupler 11, and part of the flexible joint 9, are provided with supporting means for holding this portion of the connection up from the track when its coupler is not in engagement with 35 a mating coupler. This supporting means is so constructed and arranged as to allow the flexibility at the articulations of the conduit structure requisite for coupling and uncoupling the same, and for giving the structure the capacity to adapt itself to the relative shifting movements of the cars between 40 which the connection is located. The ends of the adjacent cars of a railway train may rise and fall, one with respect to the other, 45 may be displaced angularly one from another, and in the starting up and stopping of the train, may recede from and approach one another. In fact, these movements may be combined, and it has been one of the problems, in providing an all-metal substitute 50 for the rubber hoses commonly used for connecting the train pipe of a railway train, to design a structure made up of rigid parts articulated in such a way as to give the necessary flexibility while avoiding arrangements which might, with certain movements 55 of the cars, bring parts of the structure into too close proximity to the roadbed. The relatively movable parts of the flexible structure herein shown are so proportioned and disposed, one with respect to the other, that all possible movements of the car are provided for without bringing any part of the 60 structure close to the track. When one of these flexible structures, however, is not in 65

coupled relation with another such structure (or equivalent element), as will be the case at the end of the train, the structure will sag backwardly and downwardly, the parts flexing at the pivotal joints so that the coupler 70 11 is likely to drag along the track. To prevent this, a chain or other flexible member is provided which extends from the outer end of the structure to the upper or fixed end thereof, or to some fixed point on 75 the car adjacent thereto. Except for extreme movements of the cars, particularly movements of one car away from the other, it will be possible to use a non-extensible chain provided that the chain is arranged to extend in the diagonal direction as shown 80 in the drawings. Preferably, however, in order to make certain the accommodation of the connection to all possible movements of the cars, the supporting member is made so 85 that it will stretch to a certain extent under stress developed by the relative movements of the cars. With this end in view, the supporting member is preferably composed of two links or sections of chain 46 and 47, between 90 which is interposed a coiled spring 48 adapted to be put under compression by a longitudinal pull on the links. The link 47 is connected at its lower end to a lug or eye 49 on the horizontal conduit 8, and is 95 connected at its upper end to an eye 50 at the lower end of a shank 51 extending through compression spring 48 and having a head 52 engaging the upper end of the spring. The shank 51 passes slidably 100 through an opening in the head 53 of the casing 54, which casing encloses the spring 48 with the head 53 bearing against the other end of the spring 48 from the head 52. The upper link or chain section 46 connects an 105 eye 55 on casing 54 with some upper fixed portion of the flexible structure or with some adjacent portion of the car. In the arrangement here shown, the upper end of link 46 is connected to an eye 56 on an annular member 57 swiveled on the neck portion 5 at the upper end of socket member 13. This flexible connection for supporting the lower portion of the conduit structure when not connected to a mating coupling is claimed 110 in our parent application, Serial No. 544-448, hereinabove referred to.

All of the flexible structures, including the supporting device for the horizontal section 8, except the adapter 1, may be manufactured and assembled as a unit. The proper adapter is screwed into the end valve 2. The flexible structure may then be attached to the adapter by rotating the socket member 13, which can turn with respect to the lower 120 portions of the flexible structure by reason of the swiveled connection between yoke 17 and the ball member 27.

In operation, the flexible metallic conduit structure is coupled up with or uncoupled 130

from a similar flexible structure on an adjacent car, or with an equivalent connecting element such as the rubber hose connection in common use in this situation, by the usual manipulations of the coupler heads. If the couplers are of the so-called gravity type, as shown in the drawings, the flexible structure may be flexed at the different pivotal points, to allow the forward end of the coupler to 5 be tilted upwardly and downwardly to allow the cams of one coupler to ride over those of the other. The swiveled relation of the parts will also allow the vertical faces of the mating couplers to be accurately fitted one 10 against the other, even though the end valves may not be set accurately at the same angle on their respective car train pipes. These 15 flexible and swiveled connections will permit all ordinary relative movements as between 20 the cars, and allow the necessary flexibility of the connection under ordinary service conditions. In case of an extreme movement of 25 separation between the cars, involving a stress on the supporting member for the horizontal portion of the conduit structure, this supporting member can elongate because of the interposition therein of the compression spring 48. When the flexible conduit structure is not coupled up with a mating 30 element, as will be the case at the end of the train, the supporting member is already in place to hold up this portion of the conduit structure so that it will not be injured by falling into contact with the ties or 35 roadbed.

We claim:

1. In combination with the articulated elements of a flexible metallic conduit, a pivot

construction forming a part of said articulation comprising a bushing set into one of 46 said elements, the inner end of which is closed, and a pivot stud secured to the other element and projecting into said bushing, the pivot stud being provided with lubricant ducts leading from the inner end of the 45 same to the bearing surfaces of said stud and bushing.

2. In combination with the articulated elements of a flexible metallic conduit, a pivot 50 construction forming a part of said articulation comprising a bushing set into one of said elements, the inner end of which is closed, a pivot stud secured to the other element and projecting into said bushing and 55 formed with a central longitudinal lubricant duct, and transverse ducts leading therefrom to the bearing surfaces of the stud and bushing.

3. In combination with the articulated elements of a flexible metallic conduit, a pivot 60 construction forming a part of said articulation comprising a bushing, the inner end of which is closed, the bushing being exteriorly threaded so that it may be removably screwed into one of the elements of the 65 articulation, and a pivot stud having a threaded portion to be screwed into another element of the articulation and a cylindrical portion adapted to project into and pivot within the bushing, the stud being provided 70 with a lubricant duct leading from the inner end of same to the cylindrical bearing surface.

EGBERT H. GOLD.
EDWARD A. RUSSELL.
